CARTRIDGE FEED-BELT FOR MACHINE GUNS AND METHOD OF MAKING THE SAME

James A. Hendley, Middletown, Conn., assignor to The Russell Manufacturing Company, Middletown, Conn., a corporation of Connecticut

Application July 22, 1942, Serial No. 451,972

6 Claims. (Cl. 139—390)

This invention relates to improvements in woven cartridge feed-belts for machine guns, and methods of making the same.

One object of this invention is to provide an improved two-ply woven cartridge feed-belt for machine guns in which a single weft strand is alternately woven with warp strands of the different plies.

Another object of this invention is to provide an improved method of making the foregoing cartridge feed-belts.

With the above and other objects in view, as will appear to those skilled in the art from the present disclosure, this invention includes all features in the said disclosure which are novel over the prior art.

In the accompanying drawings forming part of the present disclosure, in which certain ways of carrying out the invention are shown for illustrative purposes:

Fig. 1 is an elevational view of a portion of a feed-belt made in accordance with the present invention;

Fig. 2 is an enlarged elevational view of a fragment of the feed-belt shown in Fig. 1 so as to illustrate the weave construction;

Fig. 3 is an edge view of Fig. 2 with cartridges shown in certain of the pockets;

Fig. 4 is an enlarged sectional view on line 4—4 of Fig. 2;

Fig. 5 is an elevational view similar to Fig. 2 but illustrating a fragment of belt in the process of manufacture;

Fig. 6 is a schematic elevational view of a feed-belt with one ply of Fig. 4 shown swung down to a position below the other ply thereof, and illustrating the mode of forming various portions of a pocket at successive stages of manufacture;

Fig. 7 is a formalized edge view of the feed-belt of Fig. 6;

Fig. 8 is a schematic view similar to Fig. 6 of a modified form of construction;

Fig. 9 is an elevational view similar to Fig. 2 of a modified form of feed-belt but with the rear or cartridge edge of the feed-belt shown in an upward position instead of downward, as in Fig. 2;

Fig. 10 is a fragmental elevational view similar to Fig. 9 but with the upper portion thereof cut away;

Fig. 11 is a cross-sectional view on line 11—11 of Fig. 9;

Fig. 12 is a view similar to Fig. 11 but with the upper portion cut away to correspond to Fig. 10;

Fig. 13 is a schematic view with one ply of

Fig. 11 swung upward above the other ply thereof to illustrate the weave construction;

Fig. 14 is a view similar to Fig. 9 but with a cartridge shown in position in a pocket; and

Fig. 15 is a side view of Fig. 14.

In the description and claims, the various parts and steps are identified by specific terms for convenience, but they are intended to be as generic in their application as the prior art will permit.

In carrying out the invention in the way illustrated in Figs. 1 to 7 of the drawings, the cartridge feed-belt 20 is formed of two plies of fabric 21 and 22 formed by weaving together two sets of warp strands 23 and 24 with a continuous weft strand 25. Part of each set of warp strands 23 and 24 cross one another from ply to ply along the line or region 26 to form a large pocket portion 27, and another portion of each set of warps 23 and 24 cross over from ply to ply twice as often along the lines or regions 28 and 29 to form a small pocket portion 30, the two pocket portions 27 and 30 together constituting a cartridge-receiving pocket 31.

The weft or filling strand 25 is woven as a continuous strand with the sets of warp strands 23 and 24 as will now be explained. Referring to Fig. 6, and starting to consider the weft strand 25 at the point or location 32 in the ply 21 adjacent the warp cross-over region 26, the weft strand 25 is reversed back and forth at opposite edges of the ply 21 to produce the selvage-loops 33 at opposite ends of the weft portions or picks 34 of the weft strand 25. When the weft strand 25 reaches a location 35 adjacent the middle of a pocket 31, it is then crossed over as a loose strand portion 36 to a location 37 in the ply 22 near the start of the same pocket 31, and is then alternately reversed in direction to produce selvage-loops 38 at opposite edges of the ply 22 until the weft strand 25 reaches a location 39 near the completion of the same pocket 31, whereupon it crosses over to ply 21 as a loose strand portion 40 to a location 41 in the ply 21, whereupon it reverses itself back and forth to again produce selvage-loops 33 in ply 21 until it reaches a location 42 near the completion of the same pocket 31, whereupon it passes directly across to a location 43 on the other ply 22, then is woven to provide a reverse selvage-loop 38 and returned to a location 44 on the ply 22, whereupon it returns directly across to a location 32a on ply 21 of the next pocket 31 to be made, corresponding to the starting position 32 of the previous fully-described weaving of the imme-

diately previous or preceding pocket 31. It will thus be seen that this feed-belt can be manufactured on a single shuttle loom. And it will also be seen that by having the two strand portions 36 and 40 of the weft strand extending from near the middle or center of the pocket in one ply, flaringly and preferably loosely to locations near the opposite completion locations of the same pocket in the other ply, that when cartridges are filled into the pockets of the belt, the points of the projectiles of the cartridges will readily pass between the loose flaringly-directed strand portions 36 and 40 without the latter breaking or interfering with the filling of the belt, or with the operation of the cartridge-filled belts in a machine gun. While it is preferred to have the flaring weft-strand portions 36 and 40 at the rear edge of the belt where the projectiles project through, it will be appreciated that they could be at the front edge of the belt.

The form of the invention illustrated in Fig. 8 is similar to the form of the invention illustrated in Figs. 1 to 7, differing therefrom in certain respects. Referring to Fig. 8 in which a feed-belt 45 is formed of two plies 46 and 47 woven with a weft strand 48, the pockets 49 of which feed-belt are formed or defined by the warp cross-over regions 50, 51 and 52, and starting to consider the weft strand 48 at the point or location 53 in the ply 46 near the start of a pocket 49, the weft strand 48 is reversed back and forth at opposite edges of the ply 46 and produces selvage-loops 54 at the opposite edges of the ply 46 until the weft strand 48 reaches a location 55 near the middle of the pocket being woven, and is then crossed over as a loose strand portion 56 to a location 57 in the other ply 47 near the start of the pocket being woven, and is then continuously woven in reverse directions in the ply 47 and in being so woven produces selvage-loops 54 at opposite edges of the ply 47, and when the weft strand 48 reaches a location 58 in the ply 47 near the completion of said pocket it is then crossed over as a loose strand portion 59 to a location 60 in the ply 46 near said middle of said pocket, and is then continuously woven in reverse directions, producing selvage-loops 54 at opposite edges of the ply 46 until it reaches a location 61 in the ply 46 near the completion of said pocket. The weft strand 48 then proceeds back and forth between the plies 46 and 47 successively from location 61 to location 62, from location 63 to location 64, from location 65 to location 66, and from location 67 to location 53a to form selvage-loops 54 and complete a cycle or repeat of the weft strand 48. Inasmuch as the spacings between the weft-pick portions adjacent the edge of the ply 46 which contains the locations 55 and 60 are only schematically shown in Fig. 8, the actual spacings of the weft-pick portions will be more uniform, and the positions of locations 55 and 60 will therefore be nearer the center of the pocket than shown.

If desired, the cross-over regions 50 of the warps can be kept back as shown, from the front or cartridge-entrance edge of the belt by not crossing over any warps immediately adjacent this edge, in order to have the portions of the plies immediately adjacent the edge separate from one another throughout the length of the belt to facilitate insertion of the cartridges into the belt. Otherwise, the mode of construction and use of the belt 45 is essentially the same as has been more fully described concerning the belt 20 of Figs. 1 to 7.

In the form of the invention illustrated in Figs. 9 to 15 inclusive, a feed-belt is formed of two plies of fabric 68 and 69 made by weaving a single weft strand 70 with two sets of warps 71 and 72 and with the extra warp strands 73, which strands 73 may afterwards be cut away as will hereinafter be more fully described. The weft strand 70 is woven reversely on itself in the ply 68 to produce the selvage-loops 74 at opposite edges of the ply 68 at certain locations in the ply 68 as most clearly illustrated in Fig. 13, and the weft strand 70 is also woven in reverse directions in the other ply 69 to produce selvage-loops 74 at opposite edges of the ply 69 at certain intervals in the weaving of the belt, and at certain other intervals the weft strand 70 is woven with the extra warp strands 73 in making cross-over portions 75 and 76 between the two plies 68 and 69. Preferably, the extra warp strands 73 have relatively-large spaces between them, so that the weave at this edge of the belt will be a comparatively-loose weave where the cross-over portions 75 and 76 occur. It will also be noted from Fig. 9 that the cross-over portions 75 and 76 are relatively nearer the extreme rear edge of the belt than are the selvage-loops 74 along the same edge. Thus, after a belt is woven in the manner illustrated in Figs. 9, 11 and 13, the portion of the belt which includes the extra warp strands 73 and the weft cross-over portions 75 and 76 can be cut away so as to leave a completed belt such as is illustrated in Figs. 10 and 12.

Instead of cutting away the extra warp strands 73 and the cross-over portions 75 and 76, these can be left on as part of the belt, inasmuch as they form a very loosely-woven portion along the rear edge of the belt, and cartridges can be inserted into the belt in the usual manner in filling a machine-gun feed-belt. The length or depth of each pocket is considerably less than the length of the cartridges to be inserted therein, the cartridges extending beyond the opposite ends of the pockets, and the bullet end-portions of the cartridges poking out between the loosely-woven strand-portions 73, 75 and 76 in the manner illustrated in Figs. 14 and 15. All forms of the invention illustrated can be woven upon a single shuttle loom.

At the cross-over locations, either all of the warp strands or only part thereof could be crossed back and forth from ply to ply to form the pockets. Thus, for example, each alternate warp strand of each set of warp strands in the cross-over region could be crossed over. Where sets of warp strands are referred to, it does not mean that the same strands always form the same set, since, due to the crossing-over from ply to ply of warp strands, the identity of the warp strands forming the set in a ply will be different at different locations along the belt.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A strip-like woven cartridge feed-belt for machine guns comprising: two sets of warp strands woven with weft picks to form a two-ply cartridge feed-belt having a plurality of suc-

cessive cartridge-receiving pockets extending transversely of the belt; at least certain of the strands of each of said sets of warp strands crossing back and forth from one ply to the other to form said pockets; and said weft picks having been woven as a weft strand which at certain locations crosses back and forth from one ply to the other, and which weft strand at certain other locations reverses its direction in each ply at opposite edges of each ply; the length of each pocket being considerably less than the length of the cartridges to be inserted therein, and the pockets and the weft strand being constructed and arranged to have the cartridges extend beyond the opposite ends of the pockets and beyond the back-and-forth crossing-locations of the weft strand.

2. A strip-like woven cartridge feed-belt for machine guns comprising: two sets of warp strands woven with weft picks to form a two-ply cartridge feed-belt having a plurality of successive cartridge-receiving pockets extending transversely of the belt; at least certain of the strands of each of said sets of warp strands crossing back and forth from one ply to the other to form said pockets; and said weft picks having been woven as a weft strand which at certain locations crosses back and forth from one ply to the other along the rear edge of the belt, and which weft strand at certain other locations reverses its direction in each ply at opposite edges of each ply; the length of each pocket being considerably less than the length of the cartridges to be inserted therein, and the pockets and the weft strand being constructed and arranged to have the cartridges extend beyond the opposite ends of the pockets and beyond the back-and-forth crossing-locations of the weft strand.

3. A strip-like woven cartridge feed-belt for machine guns comprising: two sets of warp strands woven with weft picks to form a two-ply cartridge feed-belt having a plurality of successive cartridge-receiving pockets extending transversely of the belt; at least certain of the strands of each of said sets of warp strands crossing back and forth from one ply to the other to form said pockets; and said weft picks having been woven as a weft strand which at certain locations crosses back and forth from one ply to the other, there being two relatively-diverging weft-strand crossings at each said pocket; the length of each pocket being considerably less than the length of the cartridges to be inserted therein, and the pockets and the weft strand being constructed and arranged to have the cartridges extend beyond the opposite ends of the pockets and beyond the back-and-forth crossing-locations of the weft strand.

4. A strip-like woven cartridge feed-belt for machine guns comprising: two sets of warp strands woven with weft picks to form a two-ply cartridge feed-belt having a plurality of successive cartridge-receiving pockets extending transversely of the belt; at least certain of the

strands of each of said sets of warp strands crossing back and forth from one ply to the other to form said pockets; and said weft picks having been woven as a weft strand which at certain locations crosses back and forth from one ply to the other, and which weft strand at certain other locations reverses its direction in each ply at opposite edges of each ply, there being two relatively-diverging weft-strand crossings at each said pocket; the length of each pocket being considerably less than the length of the cartridges to be inserted therein, and the pockets and the weft strand being constructed and arranged to have the cartridges extend beyond the opposite ends of the pockets and beyond the back-and-forth crossing-locations of the weft strand.

5. A strip-like woven cartridge feed-belt for machine guns comprising: two sets of warp strands woven with weft picks to form a two-ply cartridge feed-belt having a plurality of successive cartridge-receiving pockets extending transversely of the belt; at least certain of the strands of each of said sets of warp strands crossing back and forth from one ply to the other to form said pockets; and said weft picks having been woven as a weft strand which at certain locations crosses back and forth from one ply to the other along one edge of the belt relatively near said edge, and which weft strand reverses its direction in each ply at certain other locations relatively farther from said edge; the length of each pocket being considerably less than the length of the cartridges to be inserted therein, and the pockets and the weft strand being constructed and arranged to have the cartridges extend beyond the opposite ends of the pockets and beyond the back-and-forth crossing-locations of the weft strand.

6. The method of making a strip-like woven cartridge feed-belt for machine guns comprising: weaving together two sets of warp strands with a weft strand to form a two-ply cartridge feed-belt having a plurality of cartridge-receiving pockets extending transversely of the belt, with at least certain of the strands of each of said sets of warp strands crossing back and forth from one ply to the other to form said pockets, said weft strand being periodically crossed back and forth from one ply to the other; said weft strand being continuously woven in reverse directions in one ply from a location near the start to a location near the middle of a pocket, then being crossed over to the other ply to a location near the start of said pocket, then being continuously woven in reverse directions in said other ply to a location near the completion of said pocket, then being crossed over to said one ply to a location near said middle of said pocket, and then being continuously woven in reverse directions in said one ply to a location near the completion of said pocket, and the corresponding portion of each other of said pockets being similarly woven.

JAMES A. HENDLEY.
